CLAIM

The ornamental design for a beam support block, as shown and described.

DESCRIPTION

The article is a beam support block for holding materials in a kiln.

FIG. 1 is a top view of the beam support block, embodying our new design.

FIG. 2 is a front view of the beam support block, the opposite side being a mirror image.

FIG. 3 is a side view of the beam support block, the opposite side being a mirror image.

FIG. 4 is a bottom view of the beam support block; and,

FIG. 5 is a perspective view of the beam support block.
